UNITED STATES PATENT OFFICE.

JOHN B. BOWERS, JOHN A. POTTER, AND CORAL B. DARNELL, OF NEWBURG,
MISSOURI.

RAIL-BOND.

1,118,731.

Specification of Letters Patent.

Patented Nov. 24, 1914

Application filed June 20, 1913. Serial No. 774,889.

To all whom it may concern:

Be it known that we, JOHN R. BOWERS, JOHN A. POTTER, and CORAL B. DARNELL, citizens of the United States, residing at 5 Newburg, in the county of Phelps, State of Missouri, have invented a new and useful Rail-Bond, of which the following is a specification.

The present invention appertains to rail joints, and aims to provide a rail joint embodying a rail bond which is adapted to be severed upon the excessive separation of the rail ends.

With the foregoing and other objects in view, which will be apparent as the description proceeds, the present invention resides in the combination and arrangement of parts and in the details of construction hereinafter described and claimed, it being understood 20 that changes in the precise embodiment of the invention herein disclosed can be made within the scope of what is claimed without departing from the spirit of the invention.

25 The invention has been illustrated in its preferred embodiment in the accompanying drawing, wherein:—

Figure 1 is a side elevation of the improved joint or chair. Fig. 2 is a sectional view taken on the line 2—2 of Fig. 1. Fig. 3 is an enlarged transverse section taken on the line 3—3 of Fig. 2.

In carrying out the invention, reference being had in detail to the drawing, there is 35 provided a rail chair embodying a base or bottom 1 having the integral angle iron sides or fish plates 2, in order that the chair may be adapted to receive the meeting ends of the rails with the fish plates 2 engaging 40 under the treads or balls of the rails. The base flanges of the rail ends are adapted to seat upon the base or bottom of the rail chair under the fish plates 2, as will be apparent.

45 In order to clamp the fish plates tightly against the rail ends when the pressure is applied to the rails, as when a locomotive or train is passing over the joint, the base or bottom 1 of the chair is arched or convexed 50 laterally from end to end, as indicated at 3. Thus, the base flanges of the rail ends seat or rest upon the central portion or ridge of the base or bottom of the rail chair, and when pressure is applied to the rail ends,

the central portion of the base or bottom will be depressed, and consequently, the fish plates will be firmly clamped against the rail ends to hold them tightly in position while the train is traversing the rail ends. Ordinarily, the fish plates 2 will be expanded slightly, to relieve the chair, as well as the rail ends, of any undue strain, except when the rail ends are weighted down by locomotive or train.

In order to spike or secure the chair to the ties, the lower flanges 5 of the fish plate are provided with spike openings 6, which coincide with similar openings 7 in the base or bottom 1 of the chair. The spikes 8 are adapted to be driven through the opening 6 and 7 into the underlying tie or ties 9, the spike openings at the respective sides being in staggered relation with respect to one another, and the base flanges of the rails being provided with elongated openings 1 through which the spikes pass, thereby maintaining the rail ends within the chair but permitting them to expand and contract due to atmospheric conditions. The rail chair is thus effectively spiked to the ties together with the rail ends.

In order to electrically connect the rail ends for purpose of block signaling, or for purpose of forming the leg of an electrical circuit, the upright flanges of the fish plate are provided with the complementary longitudinal slots or openings 11 intermediate their ends, and adjoining the meeting end of the rails. A coiled wire or elastic rail bond 12 is disposed or housed within one of the slots or openings 11 and has its ends 1 engaged through apertures provided in the webs of the rail ends intermediate the end of the slots 11, and bent within the other slot 11. The bond is thus housed within the rail chair, and may be readily and inexpensively applied to the rails to provide an efficient electrical connection or bond for the rails. The ends of the rail bond being engaged through the webs of the rail are specified also provide an important function in that, should the rails separate excessively the ends of the bond will be sheared by the ends of the slots, so as to break, or open the electrical circuit, thus interrupting the block signal system to indicate danger. In this manner, accidents may be avoided, due to the excessive separation of the rails, which

otherwise could not be guarded against. After the defect is remedied, a new bond may be easily applied to reestablish the electrical circuit. The joint as thus provided eliminates the use of bolts or other securing members for clamping the fish plates to the rails, which is a desirable feature, in that, it not only reduces the cost of the joint, but permits the rails to be readily attached or connected, especially when repairs are necessary. The present rail joint or chair may be employed for use in steam railroads, and inter-urban and city street car lines, the ordinary rail bonds being replaced by the rail bonds as above described. The present rail bond cannot be torn loose or injured by any obstacle that may be dragged or carried by the locomotive or cars, the rail bond being effectively housed within the chair.

Other advantages of the present device will be apparent to those versed in the art, it being noted that the objects aimed at have been carried out satisfactorily, and that the present device provides a desirable one for the purposes for which it is designed. The lower flange of the fish plates may be provided with longitudinal grooves 14 along

the edges of the base to permit the fish plates to yield relative to the base, if necessary.

Having described the invention, what is claimed as new is:—

In combination, a rail chair having sides and the sides having complementary slots, rails having their ends received by the chair between the sides thereof, the rail webs having apertures therethrough intermediate the ends of the said slots, and an elastic rail bond housed within one of said slots and having its terminal portions engaged through the said apertures and bent within the other slot, the ends of the said slots being arranged to shear the terminal portions of the bond should the rails separate excessively.

In testimony that we claim the foregoing as our own, we have hereto affixed our signatures in the presence of two witnesses.

JOHN R. BOWERS.
JOHN A. POTTER.
CORAL B. DARNELL.
